FIG. 2

FIG. 4

FIG. 3

INVENTOR
ALVIN ALBINSON
BY C. D. DuBois
ATTORNEY

UNITED STATES PATENT OFFICE.

ALVIN ALBINSON, OF MINNEAPOLIS, MINNESOTA.

PLASTER GAGE AND REINFORCEMENT.

1,357,018.

Specification of Letters Patent. Patented Oct. 26, 1920.

Application filed March 27, 1919. Serial No. 285,678.

To all whom it may concern:

Be it known that I, ALVIN ALBINSON, a subject of the King of Sweden, and a resident of Minneapolis, in the county of Hennepin and State of Minnesota, have invented certain new and useful Improvements in Plaster Gages and Reinforcements, of which the following is a specification.

One object of my invention is to provide an improved form of plaster gage and reinforcement that is adapted for general plaster work, and especially for corner bead, and angle gage.

Another object of my invention is to provide, in a plaster gage and reinforcement, an improved type of nail.

Another object of my invention is to provide, in a device of the class described, an improved form of reinforcement for plaster.

With these and incidental objects in view, the invention consists of certain novel features of construction and combination of parts, the essential elements of which are hereinafter described with reference to the drawing which accompanies and forms a part of this specification.

In the drawing Figure 1 is a side elevation of a portion of a room showing my improved plaster gage and reinforcement applied thereto. Fig. 2 is a sectional plan view of the same. Fig. 3 is an enlarged detail of a corner showing my gage and reinforcement applied thereto. Fig. 4 is a fragmentary side elevation of a portion of my gage and reinforcement showing the wire about to be applied to the nail. Fig. 5 is an enlarged fragmentary detail of the reinforcing wire used in the device, and Fig. 6 is a side view of the improved nail.

The improved nail comprises a spike 1 and head 2, and the head has a channel 3 running longitudinally thereof.

The reinforcing wire comprises a straight, stiff wire 4, preferably of about No. 12 gage, which has attached thereto, either by electric spot welding or mechanical means, the crimped wire 5, this wire being fastened at points 6 to the wire 4.

The wire 5 may lie in one plane or two

planes, as shown in Fig. 3, where it is used for reinforcing a corner.

In applying the reinforcement and gage to a corner, as at 7, Fig. 2, one of the nails will be applied at 8, Fig. 1, and inclined upwardly, one end of the wire 4 will be laid in the channel 3 of the nail, and when the nail is driven into the studding 9, Fig. 3, the lips 10 of the nail will be formed slightly over the wire 4, and the wire 4 will be kinked slightly, seating itself in the curved bottom 11 of the channel 3.

A suitable number of nails will be applied along the corner, as at points 12, Fig. 1, until the bottom 13 is reached, and the wire 4 gripped by each nail as it is driven into the studding, as heretofore described.

In applying the last nail at 13, the nail is preferably pointed slightly downward so that, by driving the nails at points 8 and 13 farther into the studding, wire 4 may be stretched taut, and it can be put into perfect alignment by tapping, slightly, the nails at points 12 if it is out of line.

In the general construction, using reinforced corners, the lath 14 lies on the studding 9 and plaster 15 is applied thereto and over the reinforcing wires 5, thus embedding these wires in the plaster and holding it firmly, even though it should become free from the lath.

It will be seen that at the corner 16 the wire 12 will form a metal finished corner, which may be entirely, or practically, covered by a finishing coat of plaster or paint, as desired.

The advantages of the device will be obvious, as it is cheap to manufacture, takes little labor for applying it to a job, and the wire 4 forms a perfect gage to plaster to, while, at the same time, a strong reinforcement is provided for the plaster at the corners where it is most needed.

The use of the nail in inside corners and along the junction of walls and ceiling will be obvious from the description already given.

While I have described my invention and illustrated it in one particular design, I do

not wish it understood that I limit myself to this construction, as it is evident that the application of the invention may be varied in many ways within the scope of the following claim:

Claim:

In a device of the class described the combination of a nail having a spike portion and a head portion, and lips extending upwardly from said head portion and forming

a channel therebetween, a wire gage adapted to be placed in said channel portion, whereby when the lip portions are tapped in the process of installing the device said gage will be gripped between said lip portions, 15 and a wire reinforcement passing transversely back and forth across said gage wire and attached thereto.

ALVIN ALBINSON.
